United States Patent Office.

JAMES M. BUCKLIN, OF ST. LOUIS, MISSOURI.

Letters Patent No. 98,344, dated December 28, 1869.

IMPROVED KING-BOLT FOR RAILWAY-CAR TRUCKS.

The Schedule referred to in these Letters Patent and making part of the same.

To all whom it may concern:

Be it known that I, JAMES M. BUCKLIN, of St. Louis, in the county of St. Louis, and State of Missouri, have invented a new and valuable Improvement in King-Bolts; and I do hereby declare that the following is a full, clear, and exact description of the construction and operation of the same, reference being had to the annexed drawings, making a part of this specification, and to the letters and figures of reference marked thereon.

Figure 1, of the drawings, is a top view of my invention.

Figure 2 is a central vertical section of same.

Figures 3 and 4 are details.

Figures 5 and 6 are modifications of bolt.

My invention relates to the mode of connecting the trucks to railroad-cars, and consists, mainly, in the construction and novel arrangement of devices, whereby the head of the king-bolt is made to rest on the transom, and the disconnection is made by dropping the bolt through the transom.

The objections to the king-bolt now in use are serious. This bolt rests upon the floor of the car, and must be drawn upward, in order to disconnect. Consequently the car, if a freight-car, and loaded, must be unloaded, or the freight shifted, in order to get at the head of the bolt.

If, by any accident, the lower part of the bolt is bent, it is clenched, and cannot be drawn out through the centre bearings.

It frequently happens, both on the road and in the shops, that the trucks of both passenger and freight-cars cannot be changed without lifting the body of the car high enough to clear the end of the king-bolt.

These, and many other difficulties are all obviated in the king-bolt which I have designed, as will be made evident by the following description.

The letter A of the drawings designates the transom;

B, the bolster of the truck; and

c, its centre bearing-plate.

a designates the head-plate, attached to the top of the transom by four bolts and nuts, which also secure the centre plate g under the transom.

The head-plate a is formed with an oblong slot through it.

This slot, which is lettered e in the drawings, extends entirely through the transom and its under bearing-plate.

A transverse shallow cavity, i, is formed at the commencement of the slot e in the head-plate, of sufficient depth to contain the oblong solid head of the king-bolt z.

n designates a cover, made to slide in a dovetail groove formed in the top of the head-block.

This cover prevents the king-bolt from jumping, and thereby becoming disarranged.

Instead of the solid oblong-headed bolt just described, I sometimes make use of the bolt now employed, by cutting off its round head, and substituting therefor the key and round washer, or the collar, washer, and split pin, passing through bolt and collar.

When it is required to release the bolt z from the body of the car, and detach the truck, the head of the bolt is raised above the cavity i, and turned one-quarter around, until it drops into the slot e, and through the transom, until it rests upon the centre bearing c.

When the key-headed bolt or collar-headed bolt, above described, is employed, no head-plate is necessary.

In my improvement, the bolt being easily accessible outside the car, no delay can occur in disconnecting, as there is nothing to prevent the bolt from being dropped down through the transom at pleasure.

Over seven pounds of iron may be saved in each bolt, in consequence of its shortness, as compared with the bolt now employed, which is designed to extend from the car-floor through the transom, and through the bolster of the truck.

The slot e is arranged so that its sides are cut by central circular grooves, to fit the cylindrical shank of the king-bolt, and keep it in the centre of the slot.

k designates a set-screw, arranged to fasten the cover n in place.

What I claim as my invention, and desire to secure by Letters Patent, is—

1. The king-bolt z, arranged to rest immediately on the transom of railroad-cars, and constructed to drop through the transom in disconnecting the truck.

2. In combination with a railroad-car, the transom A, having central oblong slot e, with upright bearing-grooves, constructed and arranged to operate as specified.

3. In combination with the transom of a railroad-car, the oblong-headed bolt z, oblong slot e, and transverse seat i, with cover n, constructed and arranged to operate as specified.

In testimony that I claim the above, I have hereunto subscribed my name, in the presence of two witnesses.

JAMES M. BUCKLIN.
